ELECTRICAL CONNECTION.

Application filed August 29, 1927. Serial No. 216,078.

This invention relates to improvements in electrical connections and more particularly to a flexible connection to a tilting mercury tube switch.

5 Switches of this character comprise a sealed glass tube having two or more spaced apart terminals, in accordance with the number of circuits to be controlled, entering through and sealed in the walls thereof and 10 containing a sufficient amount of electrical conducting fluid, such as mercury, so that when the tube is tilted with one end lowermost the fluid will flow into that end and close the circuit between the terminals in that 15 end and when tilted in the opposite direction, the conducting fluid will flow into that end and break the circuit between the terminals first mentioned. Switches of this character are mounted upon mechanisms which when 20 actuated will impart a quick movement to the tube so that it will be moved with a snap from one position to the other, in order to make a quick make or break in the circuits controlled thereby without excessive 25 arcing. It is, therefore, necessary to provide a flexible connection between the terminals of the circuits carried on the glass tube and the conductors of the circuits leading thereto. The most efficient terminals 30 comprise short lengths of small stiff wire sealed in the glass wall and extending a short distance on each side thereof having the interior ends provided with enlarged contact portions and the exterior portions adapted 35 to be connected to the circuit conductor. These wires of the terminals passing through the glass walls are usually termed "lead-in wires."

40 Mercury tube switches are employed to control circuits in many electrically-operated devices, such as electric sign flashers, oil burning and refrigerating plants, and the like, in which the tube is actuated many 45 times a day during the normal operation of the device to which it is applied. It is, therefore, necessary that the lead-in wires of the mercury tubes be provided with a 50 connection to the conductors of the circuit, or circuits, controlled by it which will be 55 flexible at all times, during long periods of operation, after long periods of rest, and be of indefinite life as many of these switches are designed to be operated millions of times during the operation of the devices with 60 which they are employed. It is preferable to connect the conductors of the circuits to

be controlled to stationary binding posts in proximity to the tilting switch and connect these binding posts by flexible leads to the lead-in wires of the mercury tube. It 60 has been found in practice that it is very difficult to make a good connection between the lead-in wires and a flexible lead comprising a single flexible wire as the two must be soldered together to form a good electrical connection and the constant flexing of the lead at the same place just above its rigid joint soon causes it to break. Most 65 flexible conductors comprise a plurality of strands of very fine wires, however, as the fine wires forming the strands lie parallel to each other it is not only difficult to solder such a conductor to a lead-in wire of a mercury tube switch but also the continued 70 flexing of the same wires at the same place and in the same direction adjacent their 75 ends attached to the lead-in wires causes the individual wires of the strands to break.

It has been found that a lead of many fine wires braided together in the form of a tube will make a most desirable conductor for this purpose because a tube of many fine braided wires allows an individual adjustment of the fine wires when flexed so that there is no continued sharp bending of any one wire during the operation of the mercury tube switch. It is an object of this invention to provide an improved manner in which to form an electrical connection between the short rigid projecting lead-in wires of a mercury tube switch and a tubular lead formed of many fine wires braided together which will withstand indefinite flexation of the lead adjacent the switch without disrupting the joint or breaking the 85 lead.

While the preferred forms of this invention are illustrated on the accompanying sheet of drawing, it is to be understood that minor detail changes may be made without 90 departing from the scope thereof.

In the drawing:

Figure 1 is a vertical sectional view taken along the longitudinal center line of a commercial mercury tube switch, illustrating one lead-in wire unattached and three lead-in wires having flexible leads secured thereto in accordance with different forms of this invention.

Figure 2 is a detail view in front elevation of one form of connecting link employed in Figure 1.

Figures 3 and 4 are detail views in plan and side elevation, respectively, of another form of connecting link shown in Figure 1. Figure 5 is a detail plan view of another form of connecting link illustrated in Figure 1.

The mercury tube switch illustrated in section in Figure 1 is of commercial construction in which the lead-in wires 1 are sealed in the glass walls 2 of the mercury tube and are provided with the customary enlarged interior ends adapted to be engaged by the mercury 3 when the tube is tilted in their direction. The flexible lead 4 is illustrated as comprising a tubular conductor 4 of fine wires braided together with an insulating sheathing 5 of commercial type thereabout. In accordance with this invention, the flexible lead 4 is joined to the lead-in wires 1 by a connecting link soldered at one end within the tubular lead and soldered at the other end to the lead-in wire.

The provision of the connecting link has many advantages in simplifying the labor of assembling the switch mechanism. It is seldom that a manufacturer of switch mechanisms for the market is also able to manufacture the flexible tubular leads and the glass mercury tubes so that the leads are usually bought from an electrical supply house and the mercury tubes from a tube factory and the switch operating mechanism after manufacture must be assembled with the lead and mercury tube which requires an accurate soldering of the lead to the lead-in wire of the tube before the tube and free end of the leads are secured in place in the switch operating mechanism.

The connecting link 6 of the type illustrated in Figure 2 in detail and shown in position joined to the second from the left lead-in wire in Figure 1, comprises a short length of rigid wire similar in material and diameter to that of the lead-in wire 1. The link is shown pointed at one end. The pointed end is inserted within the interior of the tubular lead 4, as shown in Figure 1, and soldered thereto by applying the solder to the exterior of the tube, after the sheathing 5 has been pushed back from the end, which readily passes through the interstices of the braided fine wire to the body of the link to form a continuous joint about its entire surface. As the lead and link are both products of the electrical supply house, this connection is properly made there in the production of the lead for the market. The electrical supply house also provides as a part of the lead the sleeve of fabric or insulating material 7 snugly engaging the exterior of the sheathing 5, the purpose of which will be hereinafter described.

It is then seen that the lead complete can be supplied by the electrical supply house

and is ready for attachment to the lead-in wire by the assembler of the switch. While it requires careful and accurate handling of the link to be inserted within the tubular lead and careful and accurate soldering of these parts to each other, it requires less time, care, or accuracy to assemble the lead and tube. As shown, about one half of the link is inserted within and secured to the tubular conductor so that in assembling the lead and tube, the projecting exterior portion of the link is placed against the exterior part of the lead-in wire 1 and solder applied to complete the electrical connection, thereafter the sleeve 7 is drawn down until it contacts with the glass body of the tube 2 about the lead-in wire and completes an insulated connection between the tube and lead.

The connection between the lead-in wire and flexible lead shown at the left of Figure 1 is one which is preferable when it is desired to have the lead extend in a direction at right angles to the switch tube, as shown, and in such case the link 6 is preferably a straight piece of wire, as illustrated in Figure 2, which can be placed parallel to the lead-in wire and be in engagement therewith throughout its length. In some cases it is desirable to connect the lead so that it will extend parallel to the longitudinal center line of the tube. In such cases the exterior portion of the lead-in wire would have to be bent at right angles to itself which not only is a very delicate operation after it has been sealed in the glass wall but the bending of the stiff wire and the strain upon the bend thereafter during the continued operation of the switch produces an undesirable weakness. To meet these conditions, this invention contemplates the formation of the connecting link 6, as shown in Figure 5, by providing at the lower end a loop 8 before the link is attached to the tubular conductor. As shown, the loop 8 is in prolongation of the main body of the link and is of such inner diameter as to pass over and snugly engage the end of the lead-in wire, as illustrated at the extreme right of Figure 1, and when in proper position there in a complete electrical connection is made by soldering the loop to the lead-in wire. This invention also contemplates applying this means of connection for a lead, extending at right angles to the tube, by forming the loop 8 at right angles to the main body of the link, as shown in Figures 3 and 4. The loop 8 is inserted over the lead-in wire and soldered thereto, as illustrated in the second lead from the right of Figure 1.

What I claim is:

1. An electrical connection between a flexible lead composed of a plurality of fine wires braided together to form a tube and a lead-in wire sealed in a glass wall and pro-

jecting thereabove, comprising a connecting link having one end received within and soldered to the tubular lead and the projecting end thereof engaging and soldered to the 5 projecting part of the lead-in wire.

2. An electrical connection between a tubular lead composed of a plurality of strands of fine wires braided together and a lead-in wire sealed in a glass wall and projecting 10 thereabove, comprising a connecting link having one end entering within the tubular lead and soldered thereto and the projecting end formed with a loop receiving and engaging the projecting lead-in wire and 15 soldered thereto.

3. An electrical connection between a tubular flexible lead formed of a plurality of strands of fine wires braided together and a projecting rigid lead-in wire sealed in the 20 glass wall of a mercury tube switch, comprising a connecting link of wire of the same

character and size as the lead-in wire having a portion engaging and soldered to the interior of the tubular lead and a portion engaging and soldered to the projecting lead- 25 in wire.

4. An electrical connection between a tubular flexible lead formed of a plurality of strands of fine wires braided together and a projecting rigid lead-in wire sealed in the 30 glass wall of a mercury tube switch, comprising a connecting link of wire of the same character and size as the lead-in wire having a portion engaging and soldered to the interior of the tubular lead and the exterior 35 portion formed in a loop in surrounding engagement and soldered to the projecting portion of the lead-in wire.

Signed at Chicago, Illinois, this 27th day of August, 1927.

KARL HUNCIKER.
